(57) **CLAIM**

The ornamental design for a “cable holder,” as shown and described.

DESCRIPTION

FIG. 1 is a front, left side, and bottom perspective view of our new design for a cable holder.

FIG. 2 is a front view of the cable holder of FIG. 1.

FIG. 3 is a top view of the cable holder of FIG. 1; and, FIG. 4 is a right side view of the cable holder of FIG. 1, the left side being a mirror image thereof.

1 Claim, 4 Drawing Sheets

FIG. 1

FIG. 2

FIG. 3

FIG. 4
